Primary Examiner — Catherine Ho

Assistant Examiner — Natalya M Rapundalo

(57) **CLAIM**

The ornamental design for a bread lame, as shown and described.

DESCRIPTION

FIG. 1 is a top front perspective view of a bread lame showing my new design.

FIG. 2 is a bottom rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a top front perspective view of the bread lame in an open position, shown in an environment of use.

The broken lines in FIGS. 2–6 and 8 show portions of the bread lame that form no part of the claimed design. The broken lines in FIG. 9 show environment and form no part of the claimed design.

1 Claim, 9 Drawing Sheets
